UNITED STATES PATENT OFFICE.

ALBERT BRANDALEONE, OF NEW YORK, N. Y.

LOCK.

1,318,837.

Specification of Letters Patent.

Patented Oct. 14, 1919.

Application filed September 9, 1916. Serial No. 119,175.

To all whom it may concern:

Be it known that I, ALBERT BRANDALEONE, a subject of the King of Italy, and a resident of the borough of Manhattan, in the county of New York, city and State of New York, have invented certain new and useful Improvements in Locks, of which the following is a specification.

The invention relates to locks, and particularly to locks adapted to be operated by a key or similar device, and among its objects are to provide a lock of this character in which the mechanism of the lock may be adjusted to various positions so as to require a great variety of keys and a key which may be adjusted to meet all the various adjustments or "combinations" of the lock; to protect the lock in such a manner that it cannot be broken or opened by instruments other than the proper key; to provide for the operation of the lock from the inside without a key and to so construct and arrange the parts that they will be relatively simple, easy to manufacture, strong and durable and dependable in their operation. Other objects of the invention will appear to those skilled in the art from the accompanying specifications and drawings.

The disadvantages of a key lock are universally recognized, and require no discussion. Combination locks of simple and inexpensive construction have been devised to take their place. The present improvements do not relate to either of these. The combination lock is objectionable for the reason that many persons are unable to remember combinations of figures, and further because a certain delay is involved in opening a combination lock. By the present improvements a lock is provided which may be varied to the extent of hundreds of thousands of combinations in one form, and by a slight change of form may be again and again made the subject of the same number of combinations, and which may be opened almost instantly by the insertion of a key. The combination may also be changed from time to time as desired so that if the key is lost or stolen or a house or locker or other inclosure provided with the lock passed into the hands of a new tenant or owner he can change the combination without making permanent change in any of the parts or

supplying new parts or requiring the services of a skilled mechanic.

The improvements are illustrated in the accompanying drawings in which—

Figure 1 is a horizontal medial section of a lock embodying the improvements, taken on the line 1—1 of Fig. 2 looking in the direction indicated by the arrows; Fig. 2 is a front elevation of the same with the knob on the inside of the lock shown in vertical section on the line 2—2 of Fig. 1, looking in the direction indicated by the arrows, and with portions of the front casing broken away; Fig. 3 is a vertical section on the line 3—3 of Fig. 1 looking in the direction indicated by the arrows in that figure; Fig. 4 is a vertical section on the line 4—4 of Fig. 1 looking in the direction indicated by the arrows; Fig. 5 is a vertical section on the line 5—5 of Fig. 1 looking in the direction indicated by the arrows; Fig. 6 is a longitudinal horizontal section substantially the same as Fig. 1, but enlarged and showing the key therein; Fig. 7 is a horizontal medial section of the key taken longitudinally; Fig. 8 is an outside end view of the key; Fig. 9 is a vertical cross-section on the line 9—9 of Fig. 7, looking in the direction indicated by the arrows; Fig. 10 is a detail in perspective of one of the spacing rods of the combination mechanism of the lock; Fig. 11 is a detail in perspective of one of the halves of the cylindrical outer casing of the lock mechanism; Fig. 12 is a detail in perspective of one of the tumbler rods with a set of tumblers thereon; Fig. 13 is a similar view of the nine blank hexagonal rings of the key; Fig. 14 is a like view of the six similar rings with one lug, and Figs. 15, 16, 17 and 18 are like views of the similar rings of the key having each five, four, three and two lugs respectively.

The barrel of the lock comprises cylinders 1 and 2 in alinement and adapted to contain the operating parts of the lock. The cylinder 1 and the inner end of the cylinder 2 are inclosed in a cylindrical casing made in two semi-cylindrical parts 3 and 4. Near the middle of this casing is an annular internal flange 5 provided with six radial projections 6 of uniform size and integral therewith, and this flange separates the inner ends of the cylinders 1 and 2.

The cylinder 2 is screw-tapped into the end of the knob 7 at 8 and turns therewith, and the cylinder 1 is turned by the key when set to the proper combination. The turning 5 of either 1 or 2 causes the casing composed of the parts 3 and 4 to turn and with it turn the bolt, to the shank 10 of which it is keyed at 9. The bolt 11 is arc-shaped and its keeper or socket 12 is similarly shaped 10 so that when the said bolt is rotated by the turning of its shank 10 it will pass through the said keeper or socket to lock or unlock the door. The knob 7 has a central bore to receive the cylinder 2 and the parts contained 15 therein and is provided with a spring latch 13 by the movement of which longitudinally of the knob or handle the engaging portion of the bolt is withdrawn from the notch 15 in the plate 16 so that the knob 20 may be turned to lock or unlock the door. The plate 16 has a notch 15 on both sides, located 180 degrees apart and by this provision the knob—on the inside of the door—may be released and turned one-half a revolution 25 to lock or unlock the door and held in the position to which it is turned. The spring 17 holds the latch normally in the notch. The knob is held in position on the plate by means of the screws 18, threaded 30 into the collar 20 of the plate the inner ends of which engage the annular slot 19 of the knob. The lock is secured to the door by means of the plate 21 to which the inturned edges 22 of the plate 16 are secured by 35 means of machine screws or other suitable fastenings.

Within the cylinder 2, and extending into the inner end of 3 is a tube 23 concentric therewith and between it and the former the 40 compression springs 24 are housed. The purpose of these springs is to restore the combination mechanism to its normal position when the key is withdrawn, and when the key is inserted in the lock the parts are 45 moved against the pressure of the said springs.

The principal parts of the combination mechanism of the lock are the rods 25 between the cylinder composed of the parts 3 50 and 4 and the tube 23, upon which are strung blocks 26. The rods—six in number—and their blocks occupy the annular space at the outer end of the casing 1 between the said tube composed of the parts 3 and 4 and 55 the tube 23, and the end or guide block 27 on each rod 25 has a lug 28 which slides in a slot 29 of 23, six of these slots being provided for the reception of these lugs. The block 30 at the extreme inner end of each 60 rod is threaded thereon and serves only the purpose of holding the others in position and abutting the spring 24. The nine blocks 26 and half block 36 are the ones active in the operation of the combination, 65 and each of the six rods is provided with

a set of these blocks, as well as of the end blocks 27 and 30. The bars 31 space and separate the rods 25 and their blocks and are also six in number. The side surfaces of the blocks being rounded so as to conform to the shape of these rods. The bars are stationary and extend from end to end of the barrel, running between the coiled springs 24 so that the said springs and the rods with their blocks work between them. 70 They are provided with coincident notches 32 at the ring 5 and of sufficient depth to permit the teeth or projections 6 to rotate through the notches. 75

The position of the half blocks 36 on 80 their rods determines the combination to be set on the key, for the reason that they must register with the teeth 6 in order to permit the cylinder 3, 4 to turn, and operate the bolt, since the blocks and their rods are 85 held from rotation by the inside knob and latch 13, and the key must therefore engage the guide or pilot blocks 27 at points in its inward travel corresponding with the distance of the half block 36 from the outer 90 end of the rod. When the key is home the ball 33 is in the socket 34 of the plug 35 fixed in the end of the tube 23, and the lock turning portions of the key may then be turned to operate the lock, provided the 95 proper combination has been set on the key.

The key consists of a hollow magazine handle 37 with turning disk 38 and a central shaft composed of a hexagonal extremity 39 and round portion 40 with binding nut 41 and rings 42 and sleeve 43, the rings being held on the end of the shank by the head 45. The handle 37 of the key has a hexagonal bore which receives and contains the rings not in actual use in the 105 particular combination set up on the outer part of the key and holds them against rotation. The sleeve 43 on the rounded portion of the key shaft has a round bore so that it may turn therein and a hexagonal 110 outer surface corresponding to the interior surfaces of the rings, and the rings may be taken off and replaced for setting or changing the combination by removing the nut 41 and then removing the shaft 40 with the 115 said rings thereon and changing their respective positions as required. The diameter and shape of the sleeve 43 and the hexagonal end 39 of the shaft are the same, and the head 45 corresponds in diameter and shape 120 with the rings 42. Between the handle of the key and the outer portion 39 are four of the rings 42, and in the collar 44 at the end of the cylinder 3, 4 are longitudinal 125 grooves 46 adapted to receive the lugs or flanges of the rings and to permit them to pass therethrough. These grooves are in line with the slots 29, and as they, like the said slots, are six in number and arranged at angles of sixty degrees to each other, cor- 130

responding with the location of the lugs 48 on the rings 42, these lugs will always find passage therethrough.

The rings 42 of the key may be divided 5 into six sets, as follows:

- Six rings with one flange;
- Nine rings with two flanges;
- Six rings with three flanges;
- Three rings with four flanges, and
- 10 One ring with five;
- One ring with six, and
- Nine blanks.

The rings with flanges engage the lugs 28 of the pilot blocks 27 on the ends of the rods 25, and must therefore be so positioned on the key as to engage at the proper point in the inward travel of the key to bring the half block 36 in line with the teeth 6 when the key is home. Therefore in setting the 20 combination the blocks on the rods 25 or the ten rings on the hexagonal end of the key are first set, and the others set to correspond therewith. For instance, in the combination shown partly in Figs. 1, 6 and 25 7, one of the half blocks is the fourth one from the outer end of the rod—not counting the pilot block 28—and the ring with the flange intended to engage that string is therefore fourth from the forward end of 30 the key, while the other half block is the seventh from the end of its rod and the corresponding key ring seventh from the end of the key.

Assuming that the combination illustrated in the said figures is 2 3 4 6 7 9, and assuming that the rings and blocks are numbered, from the outer extremity of the key and from the pilot block respectively, in addition to the members set at 4 and 7 the 40 remaining four half blocks and four key rings must be set at 2, 3, 6 and 9. It will be seen that the combinations possible are so numerous as to be practically beyond the realm of chance discovery, and that these 45 combinations may be changed from time to time as desired by simply removing the blocks and rings and rearranging them. It is also possible to have a combination consisting of two or more numbers of the same 50 denomination. This is provided for by the multiple flanged rings, and the set of rings above enumerated is merely an example of the sets which may be varied within wide limits.

55 In setting the combination 10 rings are set on the outer hexagonal end of the key shaft and the remaining rings strung on the sleeve of the rounded portion indiscriminately, since they do not enter into the combination proper, and the four outer of them can always pass into the grooves 46 no matter how many flanges they may have or where these flanges may be located. When the rings are clamped on the key shaft by means of the tightening nut 41 the key is

ready for use, and when inserted in the lock will cause the half blocks on the six rods to register with the teeth 6 so that when turned the lugs of the said four rings will cause the cylinder 3, 4 to revolve and operate the bolt. This turning movement is permitted by the registration of the spaces provided by the half blocks with the teeth, which will check the turning movement under all other conditions.

75 The setting of the lock is accomplished by withdrawing the knob 7, after releasing the set-screw 18, and removing the cylinder 1 with the rods and their blocks therein.

The guard-plate 49 has a round casing 50 extending therefrom through the door 51 and the bolt operating cylinder rotated therein. It is threaded into the plate 21 on the opposite side of the door and held by the set-screw 52. The socket 12 is in a mortise of the jamb 53.

80 What I claim is:

1. The combination of a bolt, means adapted to extend through a door for operating said bolt, an operating knob connected with one end of said means, said means having a key aperture at its other end, a key, movable members mounted with said operating member and a checking device, the 90 said movable members being connected with the key when the key is inserted through the key aperture, and the said checking device being interposed in the path of said members, one of said members being of different form from the others and constructed when 100 brought into alignment with the checking device to pass the same and permit lock-operating movement of said other members and the key.

2. The combination of a bolt, a movably 105 mounted bolt-operating device connected therewith, a knob connected with one end of said bolt-operating device, said bolt-operating device having a key aperture at the other end, a key adapted to be inserted 110 therein, a series of movable parts adjacent said key and connected therewith, a blocking device in the path of said movable parts when the same are brought in alignment therewith, and a movable part of different 115 form from the others but mounted therewith, the said blocking device being out of the path of said member when aligned therewith.

3. The combination of a bolt, a movable 120 bolt-operating device, a key constructed to engage and operate the same, a checking device for checking the lock operating movement of said key, movable members between said key and checking device with which 125 said key is connected when in lock-operating position, means for holding said members normally in a predetermined position, and means on the key for moving said members from said position and in a direction angu- 130

- lar to said checking device, when the key is moved to lock-operating position, said means on the key and said movable members being adjustable relative to each other, and one of 5 said movable members being of different shape from the others and arranged to pass said checking device when brought in alignment therewith and moved in another direction, and to permit lock-operating move- 10 ment of the key.
4. The combination of a bolt, movable bolt-operating means connected therewith, a key constructed to engage such means and operate the lock, a plurality of series of 15 aligned blocks mounted adjacent to said lock-operating means, each series adapted to move in unison, a series of devices on the key adapted to move said series of blocks when the key is moved to lock-operating position, 20 said blocks and said key devices being interchangeable and transposable to vary their relations to members of the same series and members of the other series.
5. The combination of a bolt, movable bolt-operating means connected therewith, a key constructed to engage such means and operate the lock, a plurality of series of 25 aligned blocks mounted adjacent to said lock-operating means, each series adapted to move in unison, a series of devices on the key adapted to move said series of blocks when the key is moved to lock-operating position, 30 said blocks and said key devices being interchangeable and transposable to vary their relations to members of the same series and members of the other series, a 35 checking device arranged to prevent a movement of blocks of each series of blocks, and each series of blocks having a block formed 40 to pass said checking device and permit movement of its series and the key to operate the bolt.
6. The combination of a bolt, a key device constructed to operate said bolt, mechanism intermediate the bolt and key device for transmitting movement of the latter to the former, said key device comprising a series of transposable members having 45 projections movable to various positions laterally and longitudinally, a blocking member, a plurality of series of interchangeable blocks between said key device and blocking member, constructed to engage said blocking member and said key device and 50 prevent lateral movement of the latter, and a block in each series constructed to pass said blocking member when in alignment therewith and permit lateral movement of the key device.
- 60 7. In a lock the combination of a bolt, means for moving the said bolt, means for holding it in locked and unlocked position, said means acting to render the bolt moving means inoperative, a key comprising mem- 65 bers arranged to be placed in various posi- tions laterally and longitudinally thereof, and members connected with said bolt retaining means adjustable to various positions to correspond with the positions of the said key members, and means on one side of 70 the lock for operating the bolt moving means without the intervention of the key, the lock being provided with a key opening on another side.
8. In a lock the combination of a bolt, 75 means for moving the said bolt, means for holding it in locked and unlocked position, said means acting to render the bolt moving means inoperative, a key comprising movable members arranged to be placed in various positions and members arranged in separate groups connected with said bolt retaining holding means and adjustable to various positions to correspond with the positions of the said key members, and means 80 on one side of the lock for operating the bolt moving means without the intervention of the key, the lock being provided with a key opening on another side, said means for operating the bolt moving means being normally held against movement, and means for releasing the same connected therewith. 85
9. In a lock the combination of a locking device, means for moving the same to lock and unlock, means for normally holding said lock moving means in locking and unlocking positions, a key adapted to operate the lock moving means, means for checking the lock-operating movement of said key and means for releasing said checking means comprising movable and transposable members connected therewith and corresponding members connected with the key. 90
10. In a lock the combination of a locking device, means for moving the same to lock and unlock, means for checking said lock moving means, a key adapted to operate the lock moving means and means for releasing said checking means comprising a plurality of rods mounted to reciprocate in 105 the lock, removable pieces carried thereby capable of being transposed one of said pieces on each rod having a form different from the others and adapted to permit the bolt moving means to operate when said 110 piece is moved into proximity thereto, and means carried by the key for moving the said rods. 115
11. In a lock the combination of a locking device, means for moving the same to lock and unlock, means for checking said lock moving means, a key adapted to operate the lock moving means and means for releasing said checking means comprising a plurality of rods mounted to reciprocate in the lock, 120 removable pieces carried thereby capable of being transposed one of said pieces on each rod having a form different from the others and adapted to permit the bolt moving means to operate when moved into proxim- 125 ity thereto. 130

- ity thereto, and means carried by the key for moving the said rods, including members carried thereby adjustable to various positions determining the point in the movement of the key at which the key engages one of said rods and the position of the said piece at the end of the key movement. 5
12. In a lock the combination of a locking device, means for moving the same to lock and unlock, means for checking said lock moving means, a key adapted to operate the lock moving means and means for releasing said checking means comprising a plurality of rods mounted to reciprocate in the lock, removable pieces carried thereby capable of being transposed one of said pieces on each rod having a form different from the others and adapted to permit the bolt moving means to operate when moved into proximity thereto, and means carried by the key for moving the said rods, including members carried thereby adjustable to various positions determining the point in the movement of the key at which the key engages one of said rods and the position of the said piece at the end of the key movement, and means also carried by the said key for operating the bolt moving means engaging therewith at the end of the said releasing movement. 15
13. In a lock the combination of a series of sliding bars, adjustable blocks thereon, bolt moving means normally in the path thereof, a block carried by said bar formed to permit the bolt moving means to pass, a key, means carried thereby for operating the said sliding bars, said means being adjustable to vary the extent of movement of each bar thereby, whereby the adjustment of the said operating means on the key may be varied to correspond with the position of the said block and to bring the said blocks of each bar opposite the path of the bolt operating means at the end of the key movement. 20
14. In a lock the combination of a series of sliding bars, adjustable blocks thereon, bolt moving means normally in the path thereof, a block carried by said bar formed to permit the bolt moving means to pass, a key, means carried thereby for operating the said sliding bars, said means being adjustable to vary the extent of movement of each bar thereby, whereby the adjustment of the said operating means on the key may be varied to correspond with the position of the said block and to bring the said blocks of each bar opposite the path of the bolt operating means at the end of the key movement. 25
15. The combination of a key device, comprising a plurality of transposable members bearing a plurality of lock engaging parts, means for transposing the said members and for varying the position of the lock engaging parts with respect to parts of the lock, a lock device having an aperture therein to receive said key device, lock engaging and releasing members therein and means for varying the position of said last named members with respect to the lock engaging portions of the key device members. 30
16. The combination of a lock, provided with a key aperture therein, a bolt, means for operating said bolt, and fixed means normally for rendering said bolt operating means inoperative, a key adapted to be inserted in the said aperture, and independently adjustable devices carried by said key and arranged in longitudinal series thereon, whereby the bolt operating means are rendered operative through the action of said adjustable key devices on the insertion of the key, and separate means carried by the key whereby the bolt operating means are actuated by the turning of the key, said means for rendering the bolt operating means inoperative being adjustable to various positions to operate with said devices carried by the key. 35
17. The combination of a locking device having a key aperture therein and a key comprising a plurality of removable members adjustable laterally with respect to one another adapted to enter said aperture and a shaft on which they are mounted, said movable members of the key being movable to different positions longitudinally and laterally in relation to said shaft and one another and positioned to engage bolt operating means within the lock member, and movable lock operating means. 40
- Witness my hand this 6th day of September, 1916, at the city of New York, in the county and State of New York.
- ALBERT BRANDALEONE.
